DESIGN FOR A FISHING FLY

Floyd O. Burge, South Bend, Ind., assignor to South Bend Bait Company, South Bend, Ind.

Application October 18, 1935, Serial No. 59,116

Term of patent 14 years

To all whom it may concern:

Be it known that I, Floyd O. Burge, a citizen of the United States, residing at South Bend, in the county of St. Joseph and State of Indiana, have invented a new, original, and ornamental Design for a Fishing Fly, of which the following is a specification, reference being had to the accompanying drawing, forming a part thereof.

I claim:—

The ornamental design for a fishing fly as shown.
